Des. 241,640
Patented Sept. 28, 1976

241,640

FISHING LURE

Gary R. Miralles, 300 W. Blake St.,
Yreka, Calif. 96097

Filed July 7, 1975, Ser. No. 593,630

Term of patent 14 years

Int. Cl. D22—05

U.S. Cl. D22—27

FIG. 1

FIG. 2

FIG. 3

FIG. 4

FIG. 5

FIG. 1 is a top front perspective view of a fishing lure, showing my new design;

FIG. 2 is a side elevational view of the right hand side of FIG. 1, the opposite side being in mirror symmetry;

FIG. 3 is a top plan view of FIG. 1, the bottom plan being in substantial mirror symmetry;

FIG. 4 is a front end elevational view; and

FIG. 5 is a rear end elevational view.

I claim:

The ornamental design for a fishing lure, as shown and described.
